UNITED STATES PATENT OFFICE

131,829

DESIGN FOR A COMBINATION SLEEPING COUCH AND CABINET OR LIKE ARTICLE OF FURNITURE

Russell E. Brandenburger, Shelbyville, Ind.

Application December 27, 1941, Serial No. 104,876

Term of patent 14 years

To all whom it may concern:

Be it known that I, Russell E. Brandenburger, a citizen of the United States, residing at Shelbyville, in the county of Shelby and State of Indiana, have invented a new, original, and ornamental Design for a Combination Sleeping Couch and Cabinet or Like Article of Furniture, of which the following is a specification, reference being had to the accompanying drawing, forming part thereof, wherein is illustrated a front perspective view of a combination sleeping couch and cabinet or like article of furniture embodying my new design.

I claim:

The ornamental design for a combination sleeping couch and cabinet or like article of furniture, as shown.

RUSSELL E. BRANDENBURGER.
